UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRICAL APPARATUS.

Application filed October 23, 1919. Serial No. 332,621.

To all whom it may concern:

Be it known that I, JOHN D. HILLIARD, a citizen of the United States, residing at Schenectady, county of Schenectady, State 5 of New York, have invented certain new and useful Improvements in Electrical Apparatus, of which the following is a specification.

My invention relates to electrical apparatus in which the parts thereof are surrounded by an insulating fluid, such as oil, and particularly to electric switches having contacts separable in an insulating fluid. The object of my invention is to provide a 10 novel and improved switch of this general type in which dangerous pressures within the vessel are eliminated, throwing of oil from the switch is prevented, the possibility of secondary gas explosions is avoided, 15 danger of impairing the insulating properties of the oil is overcome, and which consists in general of an entirely new structure whereby the interrupting capacity of switches of the oil-break type may be 20 greatly increased.

Switches in which the contacts are separated beneath the surface of an insulating fluid, such as oil, have been called upon to open circuits of constantly higher voltage 25 systems and of net works constantly increasing in size and amount of energy to be interrupted, until in the switches now in use, various limitations have been met which must be solved before such switches 30 may be used in the present high energy circuits and the possibly higher energy circuits of the future. Heretofore, the problem of interrupting circuits by a switch of the oil-break type has not received the 35 careful study which the subject deserves and, as the result, therefore, of extensive tests, I have arrived at certain fundamental principles which it is necessary to incorporate in order that modern oil-break switches 40 will operate with a greatly increased rupturing capacity sufficient to fulfill modern and future requirements.

When an arc is drawn in an insulating fluid, such as oil, in the operation of an 45 oil-break switch to interrupt a circuit, some of the oil is vaporized and some dissociated by the heat of the arc and in the form of gas exerts high pressures upon the

oil vessel in a very short interval of time. It has been found from tests made that the volume of gas generated depends upon the KVA interrupted, the character of the load, and the characteristics of the breaker. This volume of gas formed produces two separate stresses, first a severe hammer blow or impulse propagated at high speed through the oil mass acting to stress the tank, and second, slower stresses produced by the expansion of the gases and by secondary gas explosions occurring in the air chamber above the oil. These second stresses are usually manifested by blowing of oil out of the tank and by distortion of the tank. The interrupting capacity of an oil-break switch, having an ample break distance, depends upon the pressure which the oil tank will stand and, other things being equal, this pressure varies with the volume of gas produced within the tank.

In oil-break switches heretofore used, the volume of gas generated by the arc, as the switch is opened, rises to the air chamber above the oil. It has been the customary practice in some types of switches to arrange baffles provided with openings within the oil vessel in an effort to cool the gases and to prevent the oil from being blown out of the vessel by the rapidly expanding gases. The air chamber above the oil is customarily opened to the air through suitable small openings or clearance spaces to permit the exit of gases but to prevent the escape of oil. In switches of this type, the volume of gas generated is large, particularly on modern high potential circuits and the pressure exerted is high, often disrupting the oil vessel and distorting the baffling means. Furthermore, venting the air chamber over the oil to the air, is found to permit of condensation of moisture within the chamber, because of changes of temperature. This moisture in condensing falls into the oil and greatly impairs its insulating properties. Again the chamber above the oil is often filled with an explosive mixture of air and gases. The rising of hot gases through the oil, due to a subsequent opening of the switch, has caused serious explosions due to the ignition, by the hot gases, of the explosive gaseous mixtures existing in the air chamber. These explo-

sive gaseous mixtures have also been ignited by static sparks.

In the switch of my invention these undesirable and limiting features have been overcome. This switch is provided with means whereby the gases evolved as the switch opens, may expand without greatly increasing the pressure within the vessel and without greatly accelerating the oil mass to produce sudden or impulse stresses. For this purpose, I provide the switch with expansion chambers containing a compressible fluid such as air or inert gas. The oil is forced into the expansion chambers by the pressure of the gas formed by the arc when the contacts separate, thus producing a cushioning effect to relieve the pressures otherwise exerted upon the oil vessel. The oil vessel in which the contacts separate is also completely filled with oil, thus eliminating the air chamber in which moisture might be condensed and in which secondary explosions may occur. I also provide means for cooling the gases as they rise to the top of the oil vessel and for permitting their exit from the switch through an opening controlled by a normally closed valve. The switch embodying my invention is also provided with means to maintain the main oil vessel completely filled with oil, thus preventing gases from becoming entrapped therein. The normal pressure within the tank may be kept constant and at any pressure desired. I thus provide a switch in which the disadvantages of existing switches are overcome, and by preventing stresses within the tank due to gas formation and deceleration of the oil mass, I provide a switch with a greatly increased interrupting capacity. The principles of my invention are also applicable to transformers in which the windings are located within a vessel containing oil and in which gases may be formed by static sparks.

The novel features which I believe to be characteristic of my invention will be definitely indicated in the claims appended hereto, while the features of construction and mode of operation will be understood by reference to the following description taken in connection with the accompanying drawings which show the preferred embodiments of my invention and in which:

Fig. 1 shows an oil-break switch, partly in section, embodying the novel features of my invention; Figs. 2, 3 and 4 are sectional views of a portion of an oil-break switch showing different combinations of the essential features of my invention; Fig. 5 is a detail view, in perspective, of a portion of the switch of Fig. 1; Fig. 6 is a detail view of a portion of an oil-break switch to which my invention may be applied, and Fig. 7 shows the application of my invention to another type of oil-break switch.

In Fig. 1 my invention is shown embodied in a switch of the oil-break type comprising an insulated tank or vessel 1 adapted to contain oil or other insulating fluid. The fixed contacts 2 of the switch are carried upon suitable insulating members or bushings 3 supported by the cover 4 for the vessel. Cooperating with the fixed contacts 2 are movable contacts 5 carried by a bridging member 6. The bridging member is carried by an insulating rod 7 extending through the top or cover 4 of the oil vessel 1 and is adapted to be actuated by any suitable operating mechanism, not shown, to move contacts 2 and 5 into and out of engagement to control the circuit through the switch. In the form of switch shown in Fig. 1, the fixed contacts 2 are surrounded by explosion or compression chambers 8 provided with insulated openings through which the contacts 5 are movable. These contacts 5 are, preferably, of the rod or plunger type. These explosion chambers 8 function, as is well known, to store up pressure during the initial opening movement to direct a blast of oil into the arc path as the movable contact leaves the chamber. Supported from the bottom of the explosion chambers 8 are insulating barrier members 9 of cylindrical shape which surround the chambers and supply the necessary insulation.

Within the tank or vessel 1 is provided a casing or barrier 10 substantially concentrically disposed and extending nearly to the bottom of the vessel but spaced away from the sides of the vessel to provide an annular space or chamber 11. The barrier 10 is properly insulated or may be formed of insulating material. The chamber 11 is hermetically closed at the top by an annular member 12. The chamber 11 formed by barrier 10 constitutes an expansion chamber or shock absorbing means for the switch, as will be described hereinafter and also serves as a means whereby the level of the oil may be varied within the vessel 1 and hence the pressure within the vessel may be varied. An outlet 13 is provided communicating with the top of chamber 11 which may be opened or closed so that with the requisite amount of oil or other insulating fluid within the tank 1, may be admitted thereto, moreover air or gas pressure can be admitted through the outlet 13 to force the oil down in the annular chamber 11 to some level such as indicated at *a* or until the level of the oil within the central or main portion of the tank is at any height desired. In the preferred embodiment of my invention, the pressure within the chamber 11 is sufficient to maintain the oil level at the top of the vessel and against cover 4 so that the tank 1 is completely filled with oil with no air chamber above the oil level. With the elimination of the ordinary air chamber,

there is no opportunity for condensation of moisture to impair the insulating properties of the oil as there is no air in the tank above the oil level. There is also no opportunity 5 for secondary explosions to occur due to the ignition of explosive gaseous mixtures above the oil by subsequently rising hot gases or by static sparks.

By exerting further pressure through outlet 13, any pressure desired may be exerted upon the oil within the tank 1, the level of the oil in chamber 11 giving an indication of the volume of gas within the expansion chambers. For indicating the level of the 15 oil within the chamber 11 and hence the volume of compression space, I provide a sight gauge or level indicator 14 comprising a hollow upright tube 15 of transparent material, in communication with the top of chamber 11 and the lower end of the tank 1. It is apparent that by suitable calibration, the level of the oil in the tube 15 and hence in chamber 11 may be controlled to maintain the tank 1 completely filled with oil at 20 25 any desired pressure. If desired, inert anhydrous gas may be used within chamber 11. By a suitable pressure regulating means connected to outlet 13, the normal pressure within the tank may be maintained constant 30 at any desired value.

The operation of an oil-break switch of the prior art with an oil vessel completely filled with oil would cause the destruction of the switch due to the stresses developed 35 by the volume of gas evolved, but I have provided means to meet this exigency in the switch structure embodying my invention. In this switch I have provided shock absorbing means for greatly reducing the stresses 40 produced as the switch operates and thus greatly increasing the energy which the switch can interrupt. This shock absorbing means comprises chambers substantially filled with a compressible fluid such as air 45 or inert gas held sealed in the chambers or entrapped in position by the oil. These chambers may have a variety of forms and are distributed within the oil tank so as to 50 be immediately available and of a capacity 55 to take care of the maximum volume of gas which may be evolved.

In Fig. 1, I have shown combined in one switch, several forms of expansion chambers. One form in which my shock absorbing 60 means is used consists of chambers 16 mounted substantially concentric with the tank 1 and supported by uprights or studs 65 secured to the casing or barrier 10.

These chambers 16, in the form shown, consist of inverted U-shaped annular rings spaced apart and mounted one above the other. These annular chambers at frequent 70 intervals are held rigidly in position and spaced relation, by insulating blocks 18 of a similar configuration, to which the studs 75

17 are secured, as is best shown in Fig. 5. A sectional view of the supporting structure for the chambers 16 is shown in Fig. 1. The chambers 16 extend around the tank 1 within the central enclosure formed by barrier 70 10 and preferably extend from the bottom to the top of the barrier 10 at certain spaced intervals. Each chamber is shaped to form a pocket which is substantially filled with air or inert gas held sealed or entrapped by 75 the oil with which the vessel is filled. The air in these chambers is adapted to be compressed by the oil to provide a cushion action, and to provide a means whereby the oil may move by the pressure exerted by the 80 evolved gases, the air thus providing an expansion means limits the stresses within the vessel 1. In a similar way the chamber 11 produced by barrier 10 also acts as an expansion chamber, pressure of the oil compressing the air or gas within the chamber and permitting of movement of oil within the tank with a consequent marked reduction in stress.

To still further provide room for expansion of the oil, I provide a receptacle or expansion chamber 19 of a dome configuration open at the bottom and movably supported upon pins 20. This chamber is preferably centrally disposed near the bottom 95 of the oil vessel 1 adjacent the lower end of barrier 10. The pins 20 are secured to the bottom of the vessel and extend up through suitable channels 21 in the chamber 19. The chamber 19 is freely movable along pins 100 20 but is limited in its upward movement by stops or nuts 22 threaded on the ends of pins 20 and adjustable thereon. Normally due to the air or inert gas filling chamber 19, the chamber floats in the position, shown 105 in Fig. 1, against stops 22. Upon opening of the switch, the oil mass in moving forces the chamber 19 down and the oil up into the chamber thereby compressing the air within the chamber 19 and providing a 110 space for the oil to be displaced by the gas from the arc.

It is thus apparent that in the switch shown in Fig. 1 three types of expansion chambers are shown, the annular chambers 115 16, the chamber 11, and chamber 19. These chambers are all below the oil surface and contain air or inert gas which is sealed or entrapped in the chamber by the insulating liquid. This air or gas is easily compressible and when the switch opens and the gases are formed by the arc, the oil is forced 120 into the expansion chambers to compress the gas in the chambers. The volume of oil entering the chambers is substantially equal 125 to the volume of gas generated. The movement of the oil into the chambers thus produces a cushioning or shock absorbing effect and practically eliminates the sudden impulse stress or hammer blow which would 130

otherwise be exerted by the oil mass and which is so disastrous to oil-break switches. Having removed this apparently limiting feature in oil circuit breaker construction, 5 it is evident that circuits of a greater energy can be interrupted.

In order to provide an exit for the gases formed as the switch opens, I provide at the top of the switch, supported by cover 10 4, a control valve 23 which consists of a float 24 supported or held up by the oil within the tank 1 and normally closing an outlet from the tank. As the gases rise to the top of the tank 1, the level of the 15 oil is forced down and consequently the float 24 falls and opens the outlet permitting the valve 23 to furnish an exit for all the gases. When all the gas has been expelled and the level of the oil rises to 20 normal position, the float 24 automatically closes to prevent any oil from being blown from the switch.

There is also carried near the top of the tank 1 above the annular chambers 16 a 25 cooling means for the gases which consists of screens or perforated members 25 between which is a layer of porous material 26 such as gravel or like material. This screen or baffle serves to break up the gas 30 mass evolved, into small streams, and acts to cool the same before its exit from the switch. In my copending application S. N. 443,440 filed Feb. 8, 1921, I claim broadly an oil switch having a gravel baffle. At 35 the same time the so-called "chimney effect" is eliminated in which the gas evolved rises in a large highly heated volume. In order to facilitate the removal of oil, an outlet 27 is provided at the bottom of the 40 tank 1.

Instead of using all the forms of expansion chambers shown in Fig. 1, I may use any one or more forms as desired, depending on the energy of the circuit to be interrupted. In Fig. 2 for instance, the barrier 10 is used alone to provide the expansion chamber 11 with its attendant functions and in this type of switch the explosion chambers 8 are omitted. In Fig. 50 3 the same type of switch is shown utilizing the expansion chamber 19 alone, while in Fig. 4 an explosion chamber type of switch is shown with the expansion chamber 11 in combination with the annular chambers 16.

The principles of my invention are equally applicable to explosion or pressure retaining chambers installed as a part of high tension switches as well as to the oil vessels themselves, as the explosion chamber may be considered as a small high pressure switch within the main switch. In the explosion chamber type of switch, the arc is drawn between the fixed and movable contacts which are surrounded by the explosion

chamber. A high pressure is developed within the chamber until the movable contact moves out of the chamber whereupon the pressure is then utilized to blast a current of oil out of the opening to interrupt the circuit. In these explosion chambers, unless the blast of oil is delivered with great rapidity, due to great pressure, its interrupting effect is impaired. According therefore, to the principles of my invention, 70 I may provide expansion chambers within the explosion chamber into which the oil within the explosion chamber may flow due to the excessive pressure developed; providing these expansion chambers, permit of 75 a greater gas generation within the pressure retaining chamber without injury to the chamber and hence a greatly increased interrupting capacity of the switch. In Fig. 6, I have shown a pressure retaining or explosion chamber 28 surrounding the fixed contacts for the switch, it being understood that such a chamber could be substituted for the explosion chamber 8 in the switch shown in Figs. 1 or 4. This chamber 80 is of usual steel construction suitably insulated with an opening in the lower wall supplied by an insulating bushing 29 through which the movable contact passes. Substantially concentrically disposed within chamber 28 is an annular member 30 spaced apart from the walls of chamber 28 forming the expansion chamber 31 for the oil within the chamber 28. This member 30 may be of insulating material or may 85 consist of insulated metal. The expansion chamber 31, as has been before described, contains air or inert gas which may be compressed to permit of expansion of the oil in the manner already set forth. This 90 expansion chamber 31 may be of the form shown or may consist of one or more annular rings of the type shown by chambers 16 of Figs. 1 and 4. In order to permit all the gases evolved to escape from the 95 explosion chamber 28, I provide a small opening or bleed hole, 32 at the top of the chamber which permits the oil to easily fill the chamber 28 and expel any gases therein.

In the switches so far described, the contacts have been separated with a downward break. My invention is equally applicable to upward break switches, as is shown in Fig. 7, where the oil vessel carries the fixed contacts 2 at the bottom of the vessel and the movable or rod contact 5 moves upwardly through the openings provided in a member 33. The member 33 is suitably supported in position and insulated. This member 100 forms below a pressure retaining or compression type of chamber in which the arc is first drawn as the contacts separate. Within this closed chamber is substantially 105 concentrically disposed an expansion 110

- chamber 34 of the annular type. This chamber is of the inverted type similar to chambers 16 of Fig. 1 and is suitably insulated or made of insulating material itself.
5. This chamber contains an inert gas or air and functions as has been described. The pressure developed within this compression chamber is utilized in compressing the gas in the expansion chamber 34 so that as the 10 contact rod 5 moves out of the opening in the baffle 33, a tremendous blast of oil is delivered into the arc path to interrupt the circuit. With this construction, the oil vessel is relieved from excessive stresses and 15 the blast of oil is ejected into the arc path during the zero part of the current wave when its action is most efficient. It is understood that an oil gauge 14, screen 25 and outlet 13 may be used in connection with 20 this type of switch, if desired, similar to that shown in Fig. 1 and any type of expansion chamber may be substituted for the form shown.
- I desire it to be understood that the novel 25 expansion chamber feature of my switch, in which pressures within the oil vessel are greatly reduced, is not limited to switches having vessels completely filled with oil, but this feature is equally applicable to 30 switches embodying an air chamber above the oil surface and improves the operation of the same.
- What I claim as new and desire to secure by Letters Patent of the United States, is:—
- 35 1. An oil switch provided with a baffle composed of an aggregation of individual bodies located beneath the normal surface of the oil and arranged in the path of the material ejected upon the opening of the 40 switch.
2. An oil switch comprising a vessel adapted to contain oil, said vessel being provided with an outlet for gases formed upon an opening of the switch and a porous mass of insulating material located beneath the normal surface of the oil within 45 said vessel and forming a plurality of extended narrow passages for the escape of said gases.
3. In an electric switch, the combination of a vessel adapted to contain insulating fluid, relatively movable cooperating contacts separable in said fluid and means located at different levels within said vessel 55 and operative in response to the generation of gases formed as said contacts separate to permit displacement of said fluid by the gases formed.
4. In an electric switch, the combination 60 of a vessel adapted to contain insulating fluid, relatively movable cooperating contacts separable in said fluid and means surrounding said contacts and located at different levels within said vessel and operative in response to the generation of gases
- formed as said contacts separate to permit displacement of said fluid by the gases formed.
5. In an electrical apparatus, the combination with a vessel adapted to contain an insulating fluid, of means within said vessel forming a chamber, the walls of which are independent of the walls of said vessel, containing a gas compressible to permit the flow of said fluid into said chamber. 75
6. In an electric switch, the combination with a vessel adapted to contain an insulating fluid, relatively movable cooperating contacts separable in said fluid, and means within said vessel formed with a passage in communication with said fluid for permitting the gases formed as said contacts separate to displace said insulating fluid without subjecting said vessel to excessive stresses. 80
7. In combination, a vessel in which an electric circuit may be interrupted, said vessel adapted to contain an insulating fluid, and means within said vessel formed with a chamber containing a gas held entrapped therein, said gas being compressed due to the movement of said fluid by the gases generated by the arc as said circuit is being interrupted. 85
8. In an electric switch, the combination with a vessel adapted to contain an insulating fluid, relatively movable cooperating contacts separable in said fluid, of a chamber beneath the level of the fluid in said vessel containing a gas, said gas being compressed by the flow of the insulating fluid into said chamber when said contacts separate. 90
9. In an electric switch, the combination with a vessel adapted to contain an insulating fluid, relatively movable cooperating contacts separable in said fluid, an inverted chamber in the fluid of said vessel and containing a gas held in said chamber by said fluid, said gas being compressed by the flow of said fluid into said chamber due to the pressure of the gases generated by the arc when the contacts separate. 100
10. In an electric switch, the combination with a vessel adapted to contain an insulating fluid, relatively movable cooperating contacts separable in said fluid, a pressure retaining chamber surrounding said contacts, and a second chamber within said pressure retaining chamber containing a gas, said gas being compressed by the pressure of the gases generated by the arc as the contacts separate to permit the entrance of said fluid within said second chamber. 115
11. In an electric switch, the combination with a vessel adapted to contain an insulating fluid, relatively movable cooperating contacts separable in said fluid, a pressure retaining chamber surrounding said contacts in which pressure is exerted by the gases formed as said contacts separate, and means 120
- 130

- within said chamber for storing up the expansive energy of said gases without subjecting said chamber to dangerous stresses.
12. In an electric switch, the combination with a vessel adapted to contain an insulating fluid, relatively movable cooperating contacts separable in said fluid, a pressure retaining chamber substantially surrounding said contacts in which pressure is exerted as said contacts separate, and a second chamber within said pressure retaining chamber containing a gas, said gas being compressed to limit the stresses upon said pressure retaining chamber.
13. In an electric switch, the combination with a vessel adapted to be filled with insulating fluid, relatively movable cooperating contacts separable in said fluid, expansion chambers distributed within said vessel containing gas sealed in said chambers by said fluid, said chambers affording sufficient space within which said fluid may flow and compress said gas to provide a space for the gases formed as the contacts separate.
14. In an electric switch, the combination with a vessel adapted to be filled with an insulating fluid, relatively movable cooperating contacts separable in said fluid, a chamber within said vessel communicating with said fluid and containing a gas, and means for varying the gas pressure within said chamber and hence the pressure exerted upon the insulating fluid in said vessel.
15. In an electric switch, the combination with a vessel adapted to be filled with an insulating fluid, relatively movable cooperating contacts separable in said fluid, and a valve held normally closed by the normal level of fluid in said vessel but automatically opened in response to the lowering of the level of said fluid below a predetermined point to vent said vessel to the air.
16. In an electric switch, the combination with a vessel adapted to be filled with an insulating fluid, relatively movable cooperating contacts separable in said fluid, and means operative by the level of fluid within said vessel to automatically vent said vessel to the air to permit the escape of gases generated within said vessel, said means operating to close said vessel to prevent the escape of oil when said gases have been expelled.
17. In an electric switch, the combination with a vessel adapted to be filled with insulating fluid, relatively movable cooperating contacts separable in said fluid, means whereby the level of fluid within said vessel may be maintained constant, means for automatically opening an outlet in response to the generation of gases within said vessel to permit their escape and closing said outlet when said gases are expelled, and means for providing a space for the flow of the insulating fluid by the pressure exerted by said gases whereby the stresses exerted upon said vessel by said gases and insulating fluid are harmless.
18. In an electric switch, the combination with a vessel adapted to contain an insulating fluid, relatively movable cooperating contacts separable in said fluid, and means for cooling and breaking up the gases generated by the arc as said contacts separate comprising a gravel baffle arranged below the level of said fluid.
19. In an electrical apparatus, the combination with a vessel adapted to contain an insulating fluid of a hollow member therein for containing a gas compressible to permit the flow thereto of said fluid.
20. In an electric switch, the combination with a vessel adapted to be filled with an insulating fluid, relatively movable cooperating contacts separable in said fluid, an outlet for said vessel normally held closed but adapted to be automatically opened to permit the exit of gases generated within said vessel, said outlet being automatically closed after said gases are expelled, and means in the path of exit of said gases for cooling the gases in their passage from said vessel.
21. In an electric switch, the combination with a vessel adapted to be filled with an insulating fluid, relatively movable cooperating contacts separable in said fluid, a chamber in said fluid containing a gas held entrapped by said fluid, and means whereby the normal volume of gas within said chamber may be controlled to adjust the level of the insulating fluid in said vessel.
22. In an electric switch, the combination with a vessel adapted to be filled with an insulating fluid, relatively movable cooperating contacts separable in said fluid, a chamber containing a gas, and means whereby gas may be admitted to said chamber to increase the pressure of fluid in said vessel.
23. In an electric switch, the combination with a vessel adapted to be filled with an insulating fluid, relatively movable cooperating contacts separable in said fluid, a member disposed within said vessel and spaced apart from the walls thereof to form a chamber, and means for admitting gas to said chamber to raise the level of fluid within said vessel.
24. In an electric switch, the combination of a vessel adapted to contain insulating fluid, a casing within said vessel forming therewith a gas chamber, relatively movable cooperating contacts separable in said fluid, and an automatically operated valve in said vessel constructed to open upon the accumulation of gas in the upper portion of the casing and to close when the gas has been displaced.
25. In an electric switch, the combination with a vessel adapted to be filled with an insulating fluid, relatively movable cooperating contacts separable in said fluid, and

inverted substantially U-shaped annular members within said vessel containing gas, said gas being compressed to provide a space for the flow of said fluid therein by pressures developed within said vessel.

26. In an electric switch, the combination with a vessel adapted to be filled with an insulating fluid, relatively movable cooperating contacts separable in said fluid, a chamber containing a gas, and annular members spaced apart and mounted substantially in alignment within said vessel, said members forming chambers containing gas, said gas being compressed to provide a space for the flow of said fluid therein by pressures developed within said vessel.

27. In an electrical apparatus, the combination with a vessel adapted to contain an insulating fluid, co-operating switch contacts separable in said fluid, and compression chambers arranged in said vessel to permit upward and downward movement of said fluid by the pressure produced upon

the interruption of the circuit at said contacts.

28. An oil switch comprising a vessel for containing oil and having an outlet for the gases formed upon the opening of the switch, a perforated container located beneath the normal surface of the oil, and a porous mass supported by said container and forming a plurality of tortuous passages for the escape of said gases.

29. In an electric switch, the combination of a vessel for containing oil, relatively movable cooperating contacts separable in said oil, and means for cooling and breaking up the gases generated by the arc formed as said contacts separate, said means comprising a receptacle having its upper and lower walls formed of screens of insulating material and a mass of gravel carried by said receptacle.

In witness whereof, I have hereunto set my hand this 21st day of October, 1919.

JOHN D. HILLIARD.
